TRANSFER MATERIAL STRIPPER

John Q. Sherman, Dayton, Ohio

Application September 19, 1931, Serial No. 563,820

14 Claims. (Cl. 197—126)

This invention relates to typewriters, and more particularly to an attachment applicable to writing machines and other manifolding apparatus for automatically separating the interleaved carbon or transfer material from used portions of associated record material. The use of continuous series connected manifolding stationery wherein continuous strips of carbon or manifolding material are interleaved between superposed strips of record material, the latter being transversely scored or perforated for detachment into successive sheets has become quite common. In such cases the carbon strip after being but once used is also torn into short sections simultaneously with the detachment of used portions of the record strips. Such use of "one time" carbon necessitates the further manual operation of individually separating the detached sheets of carbon material from between adjacent detached written sheets. This not only involves great waste of transfer material which the present invention is designed to conserve by guiding such material laterally from between the record strips prior to the detachment of used portions of the latter strips, thus preserving the carbon material in continuous unmutilated form for repeated use if desired, but it also involves waste of time necessary for such separation, thus to a considerable extent defeating the purpose of continuous series connected stationery.

By the use of diagonal guides and an auxiliary take-up or feed device disposed in laterally offset relation and operated in unison with the paper feeding movement of the writing machine platen roll or other paper feeding devices, the carbon material is extracted from between the advancing record strips after they have passed the writing position and before the used portions thereof have advanced to the tear-off position.

The object of the invention is to provide a simple and inexpensive mechanism for automatically separating the interleaved carbon material from the written record sheets and incidentally conserving the carbon material for re-use.

A further object of the invention is to simplify the operation as well as the means for separating manifolding material after completion of the writing operation, whereby the mechanism will not only be cheap in construction, but will be applicable to any standard type of writing machine, efficient in operation, automatic in action, of few operating parts and unlikely to get out of repair.

With the above primary and other incidental objects in view, as will more fully appear in the

specification, the invention consists of the features of construction, the parts and combinations thereof, and the mode of operation, or their equivalents, as hereinafter described and set forth in the claims.

Referring to the accompanying drawing wherein is shown the preferred, but obviously not necessarily the only form of the embodiment of the invention, Fig. 1 is a perspective view of a portion of a typewriter to which the present invention has been applied. Fig. 2 is a detail sectional view on line 2—2 of Fig. 1. Fig. 3 is a modification for use with a plurality of carbon sheets.

Like parts are indicated by similar characters of reference throughout the several views.

Referring to the drawing, 1 indicates a conventional form of typewriter of which 2 is the traveling platen carriage and 3 is the platen roll. The present invention is an attachment for use in association with continuous series connected manifolding stationery which ordinarily consists of continuous record strips 4—4 which are transversely scored or perforated at spaced intervals for subsequent division upon such transverse lines into succeeding sheets, and interposed continuous strips or webs 5 of transfer or carbon material.

In the ordinary operation the carbon material is transversely torn into short sections simultaneously with the detachment of the succeeding sections of record material. This, however, as before mentioned involves a great waste of material which is thus used but once and necessitates the further tedious and time wasting operation of individually separating the detached sheets of transfer and record material.

In the present construction the interposed strip or strips of carbon material are laterally diverted from between the record strips before the latter are sub-divided.

As illustrated in the drawing the present typewriter attachment comprises brackets 6 and 7 secured to opposite sides of the traveling platen carriage of the writing machine, the bracket 6 carrying an upright or supporting standard 8 from which extends downwardly into connection with the supporting bracket 7 a guide rod 9 interposed between superposed record strips 4 and disposed in diagonal relation to the path of travel of the manifolding assembly as it passes the writing position and approaches the position in which the written portions of the strip are to be detached by being torn off on the transverse division lines. There are as many guide rods 9 provided as there are transfer strips to be diverted from the manifolding assembly. Each

transfer strip is turned about the diagonally disposed guide rod 9 which thereby changes the direction of travel of the transfer strip, guiding it laterally from between the record strips which are thus left free to be collectively grasped independently of the interposed carbon strip or strips and detached from the supply portions of such record strips. The supporting bracket 6 is provided with a laterally extending arm 12 projecting beyond the typewriter frame which supports one or more reversely inclined guide rods 13 over which for convenience the strip is again turned and its direction of travel changed to one quite the reverse of the direction of travel past the writing position upon the platen roll 3. The guide rod 13 is preferably revolvably mounted in its support or provided with a roller sleeve having either a knurled or other tenacious surface. Co-acting with such inclined guide 13 is an auxiliary feeding or take-up roller 14 carried upon a revolvble shaft 15 mounted in suitable journal bearings at the top of the supporting standard 8 and at the end of the laterally extending bracket arm 12. This shaft 15 carries a bevel gear pinion 16 intermeshing with a similar bevel gear pinion 17 on the end of an actuating shaft 18 journaled in suitable bearings upon the supporting brackets. The actuating shaft 18 carries at its inner end a gear pinion 19 intermeshing with a similar gear pinion 20 upon the trunnion shaft of the platen roll 3. Thus as the platen roll 3 is rotated in the normal operation of the writing machine, it progressively advances in unison past the writing position the superposed record strips 4-4 and interposed carbon strip or strips 5. The latter, however, changes its direction of travel upon passing about the guide rod 9 and is diverted laterally from the manifolding assembly. The rotary auxiliary feeding roller 14 oscillating in unison with the platen roll 3, serves to draw the transfer strips laterally from between the record strips. Being timed for unison movement with the platen roll, it serves as a take-up preventing accumulation of slack, wrinkles or buckling of the transfer strips, but does not put active strain upon the transfer strips nor interfere with the normal feeding operation of the platen roll 3 by which the transfer strip is advanced in unison with the record strips. The record strips project sufficiently beyond the diagonal guide rod 9 to be easily grasped for the transverse tearing operation by which the written portions of the strips are detached. However in this operation the ends of the record strips are coactively grasped beyond the diagonal guide rod 9 entirely independently of the interposed transfer strip or strips. The diverted transfer strip or strips may be collected into a suitable receiver or rewound upon a roll for repeated use if so desired. However whether such material is reused or not, there is material advantage and a great saving of time in being able to detach the used portions of the record strips without the necessity of individually separating from therebetween the likewise detached portions of transfer material. In the modification disclosed in Fig. 3, a plurality of guide rods 9 have been shown to divert a plurality of transfer strips 5.

From the above description it will be apparent that there is thus provided a device of the character described possessing the particular features of advantage before enumerated as desirable, but which obviously is susceptible of modification in its form, proportions, detail construction and arrangement of parts without departing from the

principle involved or sacrificing any of its advantages.

While in order to comply with the statute the invention has been described in language more or less specific as to structural features, it is to be understood that the invention is not limited to the specific features shown, but that the means and construction herein disclosed comprise the preferred form of several modes of putting the invention into effect, and the invention is therefore claimed in any of its forms or modifications within the legitimate and valid scope of the appended claims.

Having thus described my invention, I claim:

1. A typewriter attachment, comprising a carbon paper guide disposed intermediate the paths of superposed strips of record material as they leave the writing machine and in diagonally disposed relation with the path of travel of the strips, and a take-up device for withdrawing the carbon material over said diagonal guide from between the superposed portions of record material. 15

2. The combination with a writing machine including strip feeding means for progressively advancing superposed strips of record material and an interposed strip of carbon material past writing position, of guide means for laterally diverting the carbon material from between the record strips after they have passed the writing position in unison with the advance movement of the strips, and independent means for tensioning the carbon material. 20

3. The combination with a writing machine including means for progressively feeding a manifolding assembly including superposed record strips and an interleaved carbon strip, of means for automatically drawing the carbon strip laterally from between the record strips after they have passed the writing position of the machine, and means for actuating the carbon strip drawing means by the advance feeding movement of the writing machine. 35

4. The combination with a writing machine including means for progressively feeding a manifolding assembly including superposed record strips and an interleaved carbon strip, a carbon strip guide disposed diagonally to the advancing strip intermediate the record strips about which the carbon strip is advanced, said guide operating to divert the carbon strip laterally from between the record strips, and means located beyond said diagonal guide and operated in unison with the writing machine strip feeding means for drawing the carbon strip away from the record strips. 40

5. The combination with a writing machine including means for progressively feeding a manifolding assembly including superposed record strips and an interleaved carbon strip, of strip reversing means located beyond the writing position of the writing machine, progressively diverting the interposed carbon strip into a laterally offset reverse path of travel in unison with its advance movement through the writing machine, and means for tensioning the carbon material. 55

6. The combination with a writing machine including means for progressively feeding a manifolding assembly including superposed record strips and an interleaved carbon strip, of auxiliary strip feeding means offset laterally out of the path of the strips as they leave the writing machine and engaging the interposed carbon strip to divert it from between the record strips in unison with the advance movement thereof. 70

7. The combination with a writing machine, including multiple strip feeding means of an attachment therefor, including divergently disposed guides over which certain of the strips are laterally diverted relatively to the remaining strips, and take-up means for the diverted strips actuated by the operation of the multiple strip feeding means.

8. The combination with a writing machine, including multiple strip feeding means of a guide disposed divergently with the path of travel of the multiple strips as they pass the writing position of the machine, auxiliary feeding means operatively engaging certain of the strips independently of others and drawing such strips over the guide laterally out of their initial path of travel.

9. The combination with a writing machine, including multiple strip feeding means, of a guide disposed intermediate the multiple strips and in diagonal relation with their path of travel as they leave the writing position of the machine, and over which certain strips are guided independently of the remaining strips, a second guide disposed in reverse angular relation with the first guide over which the diverted strips are further guided, and an auxiliary feeding device for the diverted strips actuated by the operation of the writing machine multiple strip feeding means.

10. The combination with a writing machine and multiple strip feeding means, of an auxiliary strip feeding means disposed laterally out of the path of the multiple strips as they pass the writing position of the writing machine, operative connections for actuating the auxiliary strip feeding means in unison with the multiple strip feeding means of the writing machine to draw certain multiple strips from the path of the remaining multiple strips after passing the writing position.

11. The combination with a writing machine and multiple strip feeding means, of means for automatically diverting an intermediate strip laterally out of the path of travel of other strips after they have passed the writing position in unison with their advance movement, and independent means for maintaining the intermedi-

ate strip taught between the feeding means and the diverting means.

12. The combination, in a writing machine for multiple superposed continuous record strips having transverse division lines upon which the strips are divisible into succeeding sections and a plurality of interposed strips of transfer material, including means for progressively advancing the strips in unison past a writing position, means for automatically diverting the interposed transfer strips from between the record strips after they have passed the writing position and before they reach the tear-off position upon which the record strips are divided upon the transverse division lines, and independent means for tensioning the transfer strips.

13. The combination, in a writing machine for multiple record strips adapted to be divided at spaced intervals into succeeding sheets and an interposed strip of transfer material, including strip feeding means for progressively advancing the strips in unison past a writing position, a strip diverting device operating in unison with the multiple strip feeding means for automatically withdrawing the transfer strip laterally from between the record strips after they have passed the writing position and before the contiguous portions of the record strips have been divided from such strips, and driving mechanism synchronized with the strip feeding means for actuating the diverting device.

14. In a writing machine for multiple record strips adapted to be divided at spaced intervals into succeeding sheets and an interposed strip of transfer material, including the combination with a strip feeding means for progressively advancing the strips in unison past a writing position, of an auxiliary feed device disposed in laterally offset relation with the path of travel of the multiple strips as they pass the writing position, and having engagement with the interposed transfer strip, and an interposed guide over which the transfer strip is drawn laterally out of the path of the multiple strips by said auxiliary feed device.
